SPREADER FOR FERTILIZER OR THE LIKE

George Leslie Wallis, 74 Lenelby Road,
Tolworth, Surbiton, England

Filed Oct. 23, 1961, Ser. No. 67,223

Term of patent 7 years

(Cl. D35—2)

FIG.3

FIG.2

FIG. 1 is a front perspective view taken from the top and one side of a spreader for fertilizer or the like embodying my new design;

FIG. 2 is a front perspective view thereof taken from the bottom and side opposite that shown in FIG. 1;

FIG. 3 is a rear elevational view thereof; and

FIG. 4 is a side elevational view taken from the right of FIG. 3.

I claim:

The ornamental design for a spreader for fertilizer or the like, as shown.
